(57) **CLAIM**

The ornamental design for a watch bezel device for relating musical keys to chords and notes on a wristwatch, as shown and described.

DESCRIPTION

FIG. 1 is a front perspective view of a first embodiment of a watch bezel device for relating musical keys to chords and notes on a wristwatch, shown in an environment of use; FIG. 2 is a front view thereof, shown without its environment;

FIG. 3 is a back view thereof;

FIG. 4 is a side view thereof;

FIG. 5 is a front perspective view of a second embodiment of a watch bezel device for relating musical keys to chords and notes on a wristwatch, shown in an environment of use; FIG. 6 is a front view thereof, shown without its environment;

FIG. 7 is a back view thereof; and,

FIG. 8 is a side view thereof.

1 Claim, 5 Drawing Sheets
